[57] CLAIM

The ornamental design for an automatic climate control unit for an automobile, as shown and described.

DESCRIPTION

FIG. 1 is a top perspective view of an automatic control unit for an automobile, showing my new design with the mounting plate shown in FIGS. 7-10, omitted for clarity of illustration;

FIG. 2 is a front elevational view thereof;

FIG. 3 is a top plan view thereof;

FIG. 4 is a right side elevational view, the opposite side being a mirror image of that shown except for the buttons;

FIG. 5 is a rear elevational view thereof;

FIG. 6 is a bottom plan view thereof;

FIG. 7 is a top plan view of my design, to which there is a mounting plate provided;

FIG. 8 is a front elevational view of the design as shown in FIG. 7, the rear being a mirror image of that shown;

FIG. 9 is an end elevational view of the design as shown in FIG. 7, the opposite end being a mirror image of that shown except for the buttons;

FIG. 10 is a bottom plan view of the design shown in FIG. 7.

The broken line showing of numerals in FIG. 1 for illustrative purposes only and forms no part of the claimed design.
